MERCAPTAN RECOVERY

Thomas F. McCormick, Oakland, and Arthur Lazar, Berkeley, Calif., assignors to Tide Water Associated Oil Company, San Francisco, Calif., a corporation of Delaware

Original application December 27, 1935, Serial No. 56,398. Divided and this application November 14, 1938, Serial No. 240,246

5 Claims. (Cl. 260—609)

This invention relates to improvements in de-sulphurizing petroleum or its distillates and has for a particular object the removal of mercaptans from cracked distillate, especially cracked gasoline.

Another object is the recovery of mercaptans in purified form and the recovery of the treating agent so that a simplified process assures a minimum treating cost far below that of heretofore known processes.

Another object is the recovery of a specific mercaptan in relatively purified form.

Another object is the effective removal of H_2S coupled with stabilization of the distillate by removal of wild gases such as methane, etc.

Another object is to recover a commercial butane substantially free from H_2S , from cracked products.

Further objects will become apparent as the invention hereinafter is more fully disclosed.

A feature of the invention comprises the removal of certain compounds contained in cracked gasoline which have a deleterious effect on the selective removal of mercaptans whereby the mercaptans are left in a condition easily susceptible of removal by themselves.

This will be better understood by stating that when mixtures of organic compounds, such as straight run gasoline, cracked gasoline and other hydrocarbon mixtures, are treated with an alkaline reagent, such as caustic soda solution, sodium carbonate solution and the like, a reaction with certain acidic compounds dissolved in the oil takes place.

Such acidic compounds may include hydrogen sulfide and mercaptans. Inasmuch as H_2S is a relatively strong acid and is relatively easily removed from the oil, such easy removal constitutes a base to work from leading to the selective removal of less strong acidic mercaptans.

The primary step includes the substantially complete removal of H_2S , preferably by the use of steps involving stabilization and fractionation of the distillate under treatment, because it has been determined that the major portion of the mercaptans present in gasolines, or cracked gasolines, is contained in a fractional part thereof, such as the first 30% to 40% of the distillation range and, for instance, between 170° and 250° F. end boiling point and therefore a combined treatment is very effective for H_2S removal and stabilization for eliminating the use of chemicals.

In accordance with this invention, therefore, a gasoline or total cracked gasoline is split into two or more fractions, according to volatility, to

yield a light fraction comprising about 20% to 50% of the cracked gasoline and a heavy fraction comprising from about 80% to 50%. This may be termed a "split treat," and the said light fraction may be treated for the removal and recovery of mercaptans so as to require a relatively light sweetening treatment thereafter.

The invention comprises a method of treatment with respect to H_2S removal without the use of chemicals which will be described.

10 While the treatment of cracked gasolines is also particularly described, it must be understood that other forms of petroleum distillates, coal tar distillates, shale oil distillates, or other hydrocarbons or mixtures of the same, are included in the scope of the invention.

In the appended drawings, Figure 1 is a descriptive flow sheet showing the treatment of both the said light and heavy fractions.

15 Figure 2 is a diagrammatic flow sheet specifically illustrating the treatment of the said light fraction for removal and recovery of mercaptans, and regeneration of the treating agent.

20 Figure 3 is a diagrammatic flow sheet illustrating a preferred method of removing H_2S from a distillate coupled with efficient fractionation thereof to provide the desired "split" stream for the light and heavy fractions which are thereby also stabilized.

25 Figure 1 is self explanatory and discloses the variations in treatments given the light and heavy fractions.

30 In Figure 2 the treatment of a light fraction is seen to comprise a general method of treating and includes the passage of total cracked distillate from any well known cracking and fractionating system 5 through a stabilizer column 6 wherein a separation of so-called "wild" vapors occurs, such as H_2S gas, methane, ethane, propane, etc., said vapors and gases being eliminated through valve 7.

35 The liquid distillate, comprising a total cracked gasoline, then passes through pipe 8 into a still, or fractionator 9, wherein a desired cut is made preferably to yield a light fraction of about 20% to 50% of the distillate and a heavy fraction of about 80% to 50%.

40 The heavy fraction is withdrawn from still 9 through valve 10 to be treated as desired. The removal of H_2S is effective in preventing or minimizing the quantity of such compounds which otherwise would be removed with the mercaptans in a later step of the process.

45 Hence, by fractionating out the low boiling constituents of a gasoline, or cracked gasoline,

up to about 40% thereof and treating this fraction separately with caustic solutions, a maximum removal of mercaptans is assured together with maximum desulphurization.

And, not only are the above factors important, but the removal of mercaptans by themselves relieves the load ordinarily thrown on the doctor treatment for sweetening wherein the mercaptans are altered to disulphides, and also the caustic solution is capable of regeneration for reuse for several cycles.

In addition to the above described treatment for selective removal of H_2S whereby a large percentage of the mercaptans remain dissolved in the light fraction, it is found that temperature has a marked effect on the equilibrium condition and that as the temperature of the mercaptan containing light fraction mixed with caustic soda solution approaches the freezing point of the said solution the solubility of the mercaptans in caustic increases in proportion.

In consequence, the treated light fraction issuing from tower 20 is passed through line 29 to a third similarly constructed contact tower 30, being cooled by cooler 31 to a point preferably just above the freezing point of a caustic solution introduced into tower 30 by pump 32 from the bottom of a fourth similarly constructed contact tower 38 through lines 33, 34, and spray 35.

The caustic solution then passes in true countercurrent flow to the light fraction through tower 30, the spent caustic containing mercaptans being withdrawn to tank 36, while the light fraction relieved of part of the mercaptans flows through line 37 to a fourth similarly constructed contact tower 38, being cooled, as before, on its way by cooler 39 to a point preferably just above the freezing point of fresh strong caustic solution supplied through line 40, cooler 41, and spray 42.

In tower 38, contact of the once treated cooled light fraction is completed with fresh caustic to finally remove all mercaptans in the caustic in the form of sodium mercaptides as far as is possible under the optimum conditions of temperature and strength of soda solution.

In order to assure the most efficient contact, pump 32 provides a rate of circulation from tower 38 back to tower 30 at a rate up to about 50%, or higher, of the volume of the light fraction under treatment, which is finally withdrawn through line 43 to undergo the usual doctor treatment for sweetening and is then a finished light fraction ready for blending to yield a finished motor fuel. Some of the advantages of thus treating the light fraction may be summarized as follows:

(1) The unsaturates present in the light fraction which are highly desired for their anti-knock value in finished gasolines are not attacked and lost as in sulphuric acid treatment.

(2) A re-run distillation with its accompanying losses may, in many cases, be dispensed with, due to the elimination of polymerization which takes place in ordinary acid treatment.

(3) The loss in octane number is not only minimized when compared with acid treatment followed by distillation but the octane value may be actually increased.

(4) The desulphurization by mercaptan removal is a maximum with the selective treatment of a light fraction.

(5) The maximum value may be obtained from

the caustic soda solution by regeneration and re-use.

The temperature to which the reacting mixture is reduced in towers 30 and 38 may be just above the freezing point of the caustic solution used up to 60° F., and the amount of caustic soda solution used ranges from about 5% to 30% by volume of the light fraction treated and is of a strength from about 3° to 20° Bé. Preferably, the caustic strength used is between 5° and 12° Bé., and about 10% by volume and the treating temperature in towers 30 and 38 and 30° to 40° F.

Caustic soda solution may be replaced by caustic potash, as is well known.

The efficiency of the process as a whole, while not dependent thereon, is materially increased by the regeneration and reuse of the spent caustic solution from tower 30, and the regeneration may be accomplished by either batch or continuous operation. While batch regeneration is effective, continuous regeneration is to be preferred in order to conform with the continuous operation of the preceding steps set forth.

In the batch regeneration, by reference to Figure 2, it will be seen that the spent caustic containing sodium mercaptides is drawn from tank 36 through line 44 to tank 45 containing a closed steam coil 46 and an open line 47 for the introduction of air, steam, or an inert gas for stripping.

A solution level X—X gives head room for the removal of the low boiling mercaptans in vapor form through pipe 48, the same being derived by the splitting up of the sodium mercaptides under the influence of heat applied through coil 46 to bring the solution to or near, the boiling point.

Alternative methods of applying open steam, air, etc., may be used. If steam alone be passed through the mixture, the mercaptan sulphur may be reduced from say 50 grams per liter to as low as 2 grams per liter. If the velocity of the steam through the mixture is great enough to cause foaming, additional steam may be passed through spray line 49 to break the foam.

Alternatively and preferably, continuous regeneration is effected by passing the spent caustic solution from tank 36 through line 44 and pump 50 to the top of a contact tower 51 containing a plurality of bubble plates 52, the caustic solution flowing down countercurrent to the heating and stripping steam or gas supplied through line 53.

In such a contact tower 51, when insulated and being 4' in diameter and 32' high, using 1.8 pounds of steam for 5 pounds of caustic solution charged, it is found that with seven plates the mercaptan sulphur content will be reduced from 40 grams per liter to 6 grams per liter. Using a higher ratio of steam to caustic the mercaptan content may be still further reduced, or the number of plates may be increased to provide an additional reduction in mercaptan sulphur.

The mercaptans are taken as overhead through line 54 to an insulated slop pot 55, wherein a separation of vapors from any caustic in the form of foam takes place, and the mercaptan vapors then pass through line 57 to a contact tower 58 containing suitable contact material 59 in which the vapors are scrubbed with water applied through pipe 60 to condense the mercaptans at a predetermined temperature and pressure.

Vapors are tapped off through line 61 and are composed largely of the more volatile mercaptans as methyl and ethyl mercaptan. These

mercaptans may be recovered by suitable absorption agents or may be liquefied by means of refrigeration or compression in the well known manner. Mercaptans condensed by the water pass to a settling tank 62 wherein the water separates by gravity to be withdrawn through pipe 63 controlled by an automatic liquid level regulator 64. The desired liquid mercaptans are drawn off through pipe 65.

Any caustic solution passed over from tower 51 and trapped out in the slop pot 55 may be returned by pump 56 for restripping in tower 51.

The regenerated caustic solution flows continuously from tower 51 into tank 66 whence it may be withdrawn through line 67 to be used as charging caustic through line 40. In similar fashion, the regenerated caustic solution from the batch treatment (when used) may be passed through line 68 to line 40.

The life of the regenerated caustic solution is not necessarily indefinite as there may be a gradual accumulation of impurities in the same which are not responsive to regenerative separation, but it may be used effectively in towers 38 and 30 for at least three cycles which gives great economy in caustic consumption.

Referring to Figure 3, a preferred method of removing H₂S from a raw cracked distillate, while stabilizing the same during fractionation to obtain the before described light and heavy fractions is shown.

In these steps, which are preferably used in place of the stabilizer column 6 and still 9 of Figure 2, the flow sheet and data represent actual refinery operations during the production of finished cracked gasoline from a raw cracked distillate having the following characteristics:

Gravity	58.2
Sulphur	per cent .75
Octane number (C. F. R. motor method)	70
Initial B. point	90
Per cent:	
5	112
10	124
20	160
30	191
40	227
50	257
60	283
70	309
80	343
90	366
95	394
End point	399
Recovery	95.0
Residue	1.0
Loss	4.0

The raw cracked distillate from the cracking stills is forced by pump 10 through line 71 into a flash tower 72, absorbing heat during its passage from partial condenser 73, heat exchangers 74 and heater 75 so that the distillate is discharged into flash tower 72 at about 362° F., or at a temperature sufficient to release H₂S, wild gases and certain desired low boiling fractions.

Flash tower 72 operated successfully and efficiently in the present invention with nine plates, but any desired number can be used, and with a suitable reflux liquid, which may conveniently be supplied from another part of the system by pump 76 and line 77, to separate up to say 25% of low boiling constituents together with the greater portion of the H₂S.

Operating flash tower 72 with entering distillate

at 362° F. and under a pressure of 265 pounds per square inch, gage, the desired light fraction is taken off as overhead with the H₂S which latter will then be found to be reduced from 0.30 gram per liter of the raw distillate down to 0.09 gram per liter in the bottoms which are withdrawn through line 78 and passed into a primary tower 79. Said bottoms are injected into primary tower 79 at a temperature of about 310° F. for rectification by removal of the remaining H₂S and light ends of the boiling range of the desired light fraction.

To this end, primary tower 79 may be a 30 plate tower, fitted with a reboiler 80 wherein the bottoms are heated to about 375° F., operated under a pressure of about 40 pounds per square inch, gage, and supplied with suitable reflux liquid through line 81 which may conveniently be supplied from an accumulator 82 wherein is collected part of the overhead from primary tower 79 which passes thereto by way of line 83 and partial condensers 73 and 84.

In primary tower 79, operating under the above described conditions, the H₂S will be reduced from 0.09 gram per liter of the entering stock to a trace in the rectified heavy fraction passing out through line 85 while the overhead (comprising constituents of the desired light fraction) passes from accumulator 82 through line 86 and condenser 87 to be collected in accumulator 88 in liquid form, incondensable gases being taken off through line 89 for recompression, absorption, or other uses.

The condensed overhead is picked up by pump 76 and passed through line 90 and heat exchanger 91 at a temperature of about 160° F. into a 34 plate secondary tower 92, being joined therein and in its passage by the vapor overhead brought from flash tower 72 through line 93.

Secondary tower 92 is provided for the purpose of stabilizing the desired light fraction by the elimination of undesired wild gases such as methane, ethane, etc., during which operation all H₂S is separated. To this end, tower 92 is provided with a reboiler 94 adapted to heat the bottoms to a temperature of about 300° F. thereby giving a temperature gradient through the column and yield an overhead having a temperature of about 120° F. at the outlet pipe 95 while operating under a pressure of about 245 pounds per square inch, gage.

The overhead from secondary tower 92 is taken through line 95 and condenser 96 to provide condensate in accumulator 97 which is forced by pump 98 through line 99 as reflux in the upper part of the tower. Excess condensate may be taken through line 100 to be used as blending propane, or for other purposes, while the incondensable wild gases and H₂S are withdrawn through line 101.

The light fraction is passed at a temperature of about 300° F. through line 103 into a 24 plate butane tower 104 wherein a cut of commercial butane is taken as overhead, the bottoms comprising the light fraction within the gasoline boiling range being withdrawn through lines 105 and 102 for any desired treatment.

A cut comprising substantially butanes and hydrocarbons of similar boiling range is desired with, for example, an absolute vapor pressure of about 24 to 75 pounds per square inch at 70° F., tower 104 may be provided with a reboiler 106 giving a bottom temperature of about 220° F. and a temperature at outlet line 107 of about 120° F. while operating under pressure of about 80

pounds per square inch, gage. Such a cut will consist chiefly of hydrocarbons containing four carbon atoms to the molecule, such as for example normal butane, normal butylene, isobutylene, and isobutane. The following is a typical example of such a cut, however the proportions of the various constituents may vary with the type of cracking operation, the type of charging stock to the cracking operation, et cetera:

	Mol. per cent
Propane	0.2
Isobutane	22.3
Isobutylene	15.2
Normal butylene	23.8
Butadiene	2.0
Normal butane	33.1
Methyl mercaptan	0.3
Isopentane and heavier	3.1

The overhead passing through line 107, reflux condensers 108 and head condenser 109, will flow as a liquid through line 110, part being used as reflux through line 111 and the remainder flowing through line 112 and coolers 113 to a treating system for the recovery of methyl mercaptan in substantially pure form. The incondensable gases are withdrawn through line 114.

It is found that by thus running a raw cracked distillate, as described, in the butane cut mercaptans are present up to about 0.35% by weight mercaptan sulphur and that the mercaptan sulphur is derived from the specific mercaptan, methyl mercaptan CH_3SH , which is removed by caustic soda solutions according to the following equation: $\text{NaOH} + \text{CH}_3\text{SH} = \text{CH}_3\text{SNa} + \text{H}_2\text{O}$.

In consequence, the butane cut from tower 164 through line 112 is treated with caustic soda solution according to the steps outlined with respect to the operation of towers 30 and 38 in Figure 2. In this case, towers 30 and 38 will be supplied with cooled caustic soda solution of about 5° to 12° Baumé strength and the cooled butane will flow countercurrent to the caustic with efficient contacting due to the structure of the towers, the reaction being conducted at about 30 to 40° F.

The spent caustic may then pass, as described in connection with Figure 2, from tower 30 to the described continuous regeneration plant when pure methyl mercaptan may be recovered from line 65.

More simply, the methyl mercaptan may be removed from the spent caustic by boiling the latter and condensing the distilled mercaptan, or by passing steam, air, or other inert stripping gas through the hot caustic solution and condensing the distilled mercaptan.

The preferred system, above outlined, for obtaining desired light and heavy fractions for separate treatments in the removal of impurities has many advantages.

It provides for the complete removal of H_2S without recourse to the chemical treatment usually necessary.

It gives improved fractionation for the desired split wherein gaps of over 20° F. between the A. S. T. M. Engler end point of the light fraction and the Engler initial boiling point of the heavy fraction can be obtained, which is important when a concentration of mercaptans has been determined in a given percentage of the raw distillate and thus limits the low boiling sulphur compounds to the light fraction.

It gives by improved fractionation a light fraction of a desired boiling range which is largely

uncontaminated with higher boiling and more refractory types of sulphur compounds or with compounds which may impair color stability.

It minimizes the use and cost of chemicals while yielding relatively pure valuable by-products.

It gives a commercial butane free from H_2S .

It yields a specific mercaptan in relatively pure form.

10 It must be understood that the preferred method of Figure 3 has been applied to the treatment of a cracked gasoline specifically for the purpose of illustration and not of limitation, inasmuch as variations in temperature, pressure, tower construction and the like are permissible depending on the required split in the boiling ranges of the raw cracked distillate, the character of the cracked gasoline and many other variables well known in the art.

20 For instance, in the removal of H_2S alone, the operation of flash tower 72 is not as important as its chief function which is the stripping of the lightest hydrocarbons from the raw distillate so that the load on the primary tower 79 is reduced and thus permits condensation of overhead vapors therefrom at ordinary cooling water temperatures and comparatively low pressures. This permits the use of a less costly primary tower 79 and cuts down the use and cost of steam used in reboiler 80 and the cost of condensing the overhead vapors with cooling mediums other than water.

30 Again, while correct control and adjustment of the operations in primary tower 79 and secondary tower 82 are important for the removal of H_2S the figures given for a particular cracked distillate may be varied to suit conditions. For instance, if it is desired to operate these towers at higher pressures, the top and bottom temperatures must be raised or, vice versa, if the pressure is reduced, the temperatures should be reduced.

40 A great many of such variables follow physical laws, the operation of which is well known to those skilled in the art, and the practice of the invention requires no other instructions to permit its use beyond those given. Ordinary laboratory controls to determine characteristics of a particular distillate will govern correct refinery control of the process.

50 The definition of the term "total cracked distillate" used herein indicates a distillate derived from cracking various stocks and is usually a distillate cut to an end point by A. S. T. M. distillation similar to normal motor fuel marketed. However, the total cracked gasoline may have an end point from 250° F. to 500° F., or higher, depending entirely on the particular fractionating process and/or equipment used.

60 As a rule, the end point on total cracked gasoline is cut with modern methods and equipment to somewhere between 350° F. and 437° F., but variations from this range are permissible within the scope of the invention and may include distillates from other sources such, for instance, as those made by polymerization of hydrocarbon gases as well as sulphur bearing distillates from other sources.

70 In order to obtain products in the most purified form, hydrogen sulphide should be first removed as described so that the selective removal of the other impurities may be readily accomplished.

This application is a division of our copending application Serial No. 56,398, filed December 27,

1935, now Patent No. 2,183,968, Dec. 19, 1939.

We claim:

1. The method of recovery of pure methyl mercaptan which comprises: passing a hydrocarbon distillate containing H₂S, methyl mercaptan and other acidic compounds into a first fractionating zone wherein said distillate is fractionated into a light fraction containing substantially all said H₂S and said methyl mercaptan and a heavy fraction comprising from about 80% to 50% of the distillate, passing said light fraction into a second fractionating zone wherein is separated all H₂S and the major portion of wild gases, passing the bottoms from said second fractionating zone to a third fractionating zone wherein is obtained as overhead a fraction containing the major portion of the methyl mercaptan but free from said other acidic bodies and having a boiling range approximately that of butane, treating the last named fraction with aqueous alkali solution to react with and dissolve the methyl mercaptan, and recovering methyl mercaptan from the reacted alkali.

2. The method of recovery of pure methyl mercaptan which comprises: passing a raw cracked gasoline containing H₂S, methyl mercaptan and other acidic bodies into a first fractionating zone wherein is removed as overhead up to 25% of the lighter constituents of the gasoline, passing the bottoms from the first fractionating zone into a second fractionating zone operated under such conditions of temperature and pressure as to remove as overhead a fraction containing substantially all the remaining H₂S and methyl mercaptan, combining the overheads from said first zone and said second zone, passing said combined overheads comprising up to 50% of said gasoline into a third fractionating zone operated under such conditions of temperature and pressure as to remove as overhead all the H₂S together with hydrocarbons having a boiling point below isobutane, passing the bottoms from said third zone to a fourth fractionating zone operated under such conditions of temperature and pressure as to remove as overhead a fraction of the approximate boiling range of butane containing methyl mercaptan and free from other acidic bodies, treating said overhead with an aqueous alkali solution, and recovering methyl mercaptan from the reacted alkali.

3. The method of recovery of pure methyl mercaptan which comprises: passing a raw cracked gasoline containing H₂S, methyl mercaptan and other acidic bodies into a first fractionating zone wherein is removed as overhead up to 25% of the lighter constituents of the gasoline, passing the bottoms from the first fractionating zone into a second fractionating zone operated under such

conditions of temperature and pressure as to remove as overhead a fraction containing substantially all the remaining H₂S and methyl mercaptan, supplying reflux to said first zone and to said second zone from condensed overhead from said second zone, combining the overheads from said first zone and said second zone, passing said combined overheads comprising up to 50% of said gasoline into a third fractionating zone operated under such conditions of temperature and pressure as to remove as overhead all the H₂S together with hydrocarbons having a boiling point below isobutane, supplying reflux to said third fractionating zone from partially condensed overhead from said third zone, passing the bottoms from said third zone to a fourth fractionating zone operated under such conditions of temperature and pressure as to remove as overhead a fraction of the approximate boiling range of butane containing methyl mercaptan and free from other acidic bodies, treating said overhead with an aqueous alkali solution, and recovering methyl mercaptan from the reacted alkali.

4. In a process wherein a butane fraction obtained from a cracked hydrocarbon distillate is treated for the recovery of methyl mercaptan, the method of preparing such a fraction free of H₂S prior to such mercaptan recovery which comprises: passing a raw cracked distillate containing H₂S, methyl mercaptan, and other acidic compounds into a first fractionating zone wherein in said distillate is fractionated into a light fraction containing substantially all said H₂S and said methyl mercaptan and a heavy fraction comprising from about 80% to 50% of the distillate, passing said light fraction into a second fractionating zone wherein is separated all H₂S and the major portion of wild gases, and passing the bottoms from said second fractionating zone into a third fractionating zone wherein is obtained as overhead a fraction containing the major portion of the methyl mercaptan but free from other acidic bodies and having a boiling range approximately that of butane.

5. In the stabilization of cracked distillates suitable in boiling range for motor fuel and containing H₂S and mercaptans, the process which comprises: splitting such a cracked distillate by fractionation to remove from 20% to 50% of the distillate as a fraction containing substantially all the H₂S in the distillate together with methyl mercaptan, fractionating said fraction to remove the H₂S and leave the mercaptan in the bottoms, then fractionating said bottoms to remove the mercaptan as overhead.

THOMAS F. McCORMICK.
ARTHUR LAZAR.
